COOLING

Filed May 14, 1924

Robert S. Blair

UNITED STATES PATENT OFFICE

ROBERT S. BLAIR, OF STAMFORD, CONNECTICUT

COOLING

Application filed May 14, 1924. Serial No. 713,184.

This invention relates to cooling and with regard to certain more specific features thereof to water cooling.

One of the objects of the invention is to provide apparatus of the above nature practical and efficient and capable of meeting the requirements of use in a highly satisfactory manner. Another object is to provide such apparatus capable of efficient operation at low cost. Another object is to provide apparatus of the above nature which is simply made and inexpensive. Another object is to provide a practical and effective art of cooling, capable of being conveniently carried on. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

25 In the accompanying drawing in which is shown one of the various possible embodiments of the mechanical features of this invention,

Figure 1 is a transverse section taken substantially along the line 1—1 of Figure 2, and,

Figure 2 is a vertical section taken substantially along the line 2—2 of Figure 1.

Similar reference characters refer to similar parts in both views of the drawing.

Referring now to the drawing in detail, there is shown a chamber 10 adapted to serve as a cooling chamber containing material to be cooled, in this instance being shown as a cooling chamber for drinking water. The bottom wall of this cooling chamber 10 comprises a sheet-metal member 11 and the side walls thereof comprise a curved sheet-metal member 12 resting upon the base 11 and secured thereto along its inner edge, for example by soldering as indicated at 13 to form a water-tight connection. These sheet-metal plates 11 and 12 may be of any suitable metal, copper for example being advantageous, since it is substantially non-corro-

sive and has suitable heat conducting properties.

As is seen in Figure 1, the upstanding plate 12 forming the side walls of the chamber 10 extends in a spiral coil about the chamber 10 and terminates, for example, at a point 14. The inner end of this coil is curved as indicated at 15, for a purpose which will later appear, and is secured as by soldering at 16, forming water-tight walls for the cooling chamber 10. Coiled about the cooling chamber 10 conjointly with the plate member 12, is a second and similar plate member 17, the coils of which extend between the adjacent coils of the plate 12 and in spaced relation thereto. The inner end of the plate 17 extends to a point 17a adjacent the curved wall 15 of the plate 12 and its outer end extends to a point 18 adjacent the outer end 14 of the coiled plate 12. There are thus provided about the cooling chamber 10, by the two coiled plates 12 and 17, a pair of parallel spiral passages 19 and 20. These two passages are connected at 15 at their inner ends so that they form one continuous passage extending substantially from the points 14 and 18 about and inwardly toward the cooling chamber 10 and thence back again.

The passages 19 and 20 formed by the coiled plates 12 and 17 are closed at their upper ends by an annular cover plate 21 preferably removably secured by means of screws 22 entering lugs 23 upon the plate 12. Suitable packing 21a is preferably interposed beneath the cover plate 21. The outer ends of these passages 19 and 20 are provided with end walls 24 and 25 respectively. Through the end wall 24 a passage 26 communicates with the passage 19, and through the end wall 25 a passage 27 communicates with the passage 20. The passage 26 is adapted for an inlet passage for a cooling medium, which entering therethrough traverses the passages 19 and 20, as indicated by the arrows and discharges through the passage 27 serving as an outlet passage.

The cooling medium preferably employed is air which is caused to move through the passages 19 and 20, as above described, preferably by means of a suitable suction in the

discharge passage 27. For example, a fan 28 may be employed, driven by an electric motor 28a. The inlet passage 26 is preferably provided with a funnel-shaped mouth 29 and a suitable screen 30 positioned therein.

The coiled plates 12 and 17 rest upon the base plate 11, as has been described, and the outer coil of the plate 12 is secured thereto as indicated at 31 in Figure 2 to form a water-tight connection therewith. In the bottom portions of the spiral passages 19 and 20 is contained water 34 which may be introduced thereto through a suitable connection 32. Positioned within the incoming passage 19 is an absorptive material 33 which may be of a suitable felt or fabric and which preferably takes the form of a sheet of the material spirally coiled and extending throughout the length of the passage 19. This absorptive material extends into the water 34 in the bottom portions of the passage 19 and is thereby kept continually moist, the water working up thereto by capillary action. The sheet-like member 33 standing upon its edge in the passage 19 is preferably spaced from both walls thereof, as shown, so that the incoming air traversing the passage 19 has access to both sides of the absorptive material. The sheet may be spaced from the walls of the passage by any suitable means such as buttons 33a secured thereto.

The air traveling inwardly through the passage 19 evaporates the water from the absorptive material 33 and is thereby cooled. This cooling action continues, gradually decreasing the temperature of the air until it reaches the innermost end 15 of the passage 19. As will be seen from Figure 1, during the latter part of this inward travel of the air its passage is closely adjacent to the cooling chamber 10 being separated therefrom only by the heat conducting wall 12, forming the side walls of the cooling chamber. The cooled air thus cools the drinking water within the cooling chamber 10. Thereupon the cooling air traverses the outgoing passage 20 which closely follows the incoming passage 19, being continually separated therefrom by only the sheet-metal heat conducting walls. The outwardly traveling cooled air within the passage 20 thus serves to cool the incoming air in the passage 19. The cooled air in its discharge is thus most effectively employed to pre-cool the incoming air, adding its cooling effect to that produced by the evaporation above described. The flow of air through the outgoing passage 20 is in the opposite direction to the flow in the incoming passage 19, so that the cooling effect of the outgoing air is applied to the incoming air at its coolest point, thence gradually progressing to the warmest point adjacent the inlet passage 26. The entire cooling effect is thus most efficiently employed to bring about a reduction

in temperature of the incoming cooling air to cool the drinking water within the cooling chamber 10.

The cover plate 21 is preferably extended inwardly over the cooling chamber 10 and may be provided, for example, with a funnel-shaped mouth 21b for supporting an inverted water bottle 35, the mouth of which extends therethrough into the cooling chamber 10. The entire device is preferably surrounded with a suitable protective casing 36 of heat insulating material, the upper portion 36a of which may be removable with the cover plate 21. Access may be had to the screws 22 through holes 37, for example, in order to remove the cover for purposes of cleaning or repair. A pipe 38 and faucet 39 provide for the removal of the cooled drinking water from the cooling chamber 10.

The fan 28 acts to create within the passages 19 and 20 a reduction in pressure whereby the air is drawn therethrough. This is of particular advantage since evaporation takes place with increased facility in an atmosphere of reduced pressure. The discharge passage 27 beyond the fan 28 opens into a chamber 40 from which exit is had through a passage 41 of restricted area to the exhaust opening 42. The casing forming the chamber 40 and narrowing to provide the restricted passage 41 provides a wall 43 substantially in line with the discharge from the fan 28. The air drawn from the discharge passage 27 impinges against the wall 43, the restricted outlet causes a building up of pressure within the chamber 40 on the discharge side of the fan and a large amount of the water contained in the air from the fan is condensed and separated therefrom in the chamber 40. The water thus separated from the discharging air flows back along the sloping lower side of the chamber 40 and back into the passage 20 to join the water 34 in the bottom portion thereof. Thus a large amount of the water which is evaporated for cooling purposes is returned to be used again by the absorbent member 33.

As shown in Figure 2 the exhaust opening 42 is preferably directed downwardly and away from the inlet opening 29. The inlet opening connected with the passage 26 is preferably positioned above the discharge passage as shown in Figure 2. The air discharged from the opening 42 is somewhat cooled after leaving the apparatus and by its being thus discharged downwardly below the intake passage the discharged air does not find its way to the inlet passage and the same air is not repeatedly used.

In order that a supply of water 34 may be continually maintained in the bottom of the passages 19 and 20 without attention, this water supply may be replenished from the interior of the cooling chamber 10 in this embodiment of the invention comprising a

water cooler. As shown in Figure 2, the absorbent sheet 33 and the sheet-metal plate 17 are cut away as at 44 to make room for an automatic valve mechanism. A float 45 rests upon the surface of the water 34 and has pivoted thereto at 46 a bell-crank lever 47. This lever 47 is pivoted upon a lug 48 secured to the sheet-metal member 12 and carries a valve 49 coacting with an opening 50 through the plate 12 which forms the wall of the cooling chamber 10. This valve 49 may be a rubber disk or of any other suitable construction. It will be seen that as the level of the water 34 drops, the float 45 dropping therewith the valve 49 is opened to permit water to flow from the cooling chamber 10 and replenish the supply 34. Immediately upon the level of the water 34 rising to the extent shown in the drawing, the valve 49 is again closed. The water 34 is thus maintained at a substantially constant level without requiring attention.

From the above it will be seen that there are herein provided an art of cooling and an apparatus for carrying on the same which embody the features of this invention and attain the objects thereof, together with many practical and useful advantages.

As many possible embodiments may be made of the mechanical features of the above invention and as the art herein described might be varied in various parts all without departing from the scope of the invention, it is to be understood that all matter herein set forth or shown in the accompanying drawings is to be interpreted as illustrative and not in a limiting sense.

I claim as my invention:

1. In apparatus of the class described, in combination, means forming a chamber to be cooled, means forming a pair of passages in substantially continuous heat-conductive relation one to the other, said passages leading respectively toward and away from said chamber and surrounding said chamber and being connected one with the other adjacent said chamber, heat-insulating means about said conduits whereby the heat-absorptive capacity of the outgoing air is restricted to absorption from the incoming air, and a vaporizable cooling agent accessible to air flowing inwardly through one of said passages adapted to be evaporated thereby and cool said air.

2. In apparatus of the class described, in combination, means forming a chamber adapted to contain a substance to be cooled, means forming a pair of passages in substantially continuous heat-conductive relation one to the other, said passages leading respectively toward and away from said chamber and being connected one with the other adjacent said chamber, means adapted to permit transmission of heat to the air within said first passage, and a source of moisture supply

accessible to air flowing inwardly through one of said passages adapted to be evaporated thereby and cool said air, the ends of said passages being so formed that the air is discharged from one passage away from the current of air flowing toward the inlet end of the other passage and at a lower point.

3. In apparatus of the class described, in combination, a cooling chamber adapted to contain a substance to be cooled, a pair of passages respectively leading toward and away from said cooling chamber in heat-conducting relation with each other and connected at their inner ends, means adapted to force a circulation of air through said passages, and a source of moisture supply accessible to air which has entered the inward passage, the respective outer ends of said passages being spaced one from the other and the outlet end of the discharge passage being substantially lower than the inlet end of the other passage.

4. In apparatus of the class described, in combination, a cooling chamber, a passage leading to said chamber, means for inducing a flow of air through said passage to said chamber, means for cooling said air in its passage to said chamber to cool the latter, and a discharge passage for leading said flow of air away from said chamber, said discharge passage discharging said air downwardly and away from the mouth of said first passage.

5. In apparatus of the class described, in combination, means forming a pair of passages arranged in spiral form and in heat-conducting relation one with the other, said passages being connected one to the other at their inner ends, means adapted to adjacent the connected ends of said passages to utilize the cooling effect of the fluid therein, means adapted to draw air serially through said passages, and a source of moisture supply accessible to incoming air and positioned to be first engaged by said incoming air after it has traveled in heat-conducting relation to the outgoing air.

6. In apparatus of the class described, in combination, a water cooler adapted to support an inverted water bottle and provided with a cooling chamber in position to seal with its water the downward mouth of said bottle, means forming a cooling jacket about said chamber, a passage adapted to lead air toward said cooling jacket, means adapted to utilize the air discharged from said jacket to absorb heat, means adapted to cause a flow of air through said passage, a source of moisture supply accessible to said air and comprising an absorbent member, and automatically controlled means adapted to supply said absorbent member with water from said chamber.

7. In apparatus of the class described, in combination, a cooling chamber, a passage for cooling fluid to cool said chamber com-

prising an incoming passage and a discharge passage connected at their inner ends adjacent said chamber and extending throughout their lengths substantially parallel to each other in heat-conducting relation, suction means in said discharge passage adapted to draw through said two passages a flow of air, and means adapted to cool by evaporation said air prior to entering said discharge passage.

8. In apparatus of the class described, in combination, a source of moisture supply, means adapted to utilize the cooling effect of the evaporation thereof, means adapted to draw air over said source of moisture supply and thereby reduce the air pressure thereon, and means adapted to subject the air used in said evaporation to separation of its moisture under a higher pressure.

9. In apparatus of the class described, in combination, means forming a pair of passages in heat-conducting relation throughout, said passages being connected at their inner ends, means adapted to draw air serially through said passages, a source of moisture supply exposed to air flowing through said passages, means adapted to utilize the cooling effect of evaporation of said moisture, means adapted to separate moisture from the discharge end of the outgoing passage and return the same to said source of moisture supply, and heat-insulating means restricting the access of heat to the outgoing passage to that received from the incoming passage.

10. In apparatus of the class described, in combination, means forming a substantially flat air-conducting passage, absorptive means positioned in said passage and spaced from its walls and exposed on all sides to a current of air therethrough, a source of moisture supply in operative relation to said absorptive means, and means adapted to utilize the cooling effect of evaporation from said absorptive member.

11. In apparatus of the class described, in combination, a cooling chamber, a heat-conducting jacket about said chamber, a pair of parallel passages spirally coiled about said chamber and each connected with said jacket at its inner end, means adapted to draw air serially through said passages, said passages being free from cross-connection and so positioned that the single current in each passage is embraced directly by serially spaced coils in the other, and a vaporizable cooling agent exposed to the air flowing through said passages prior to its entry into the discharge passage.

12. In apparatus of the class described, in combination, a cooling chamber, a circulating passage for cooling fluid to cool said chamber comprising a circuitous passage for leading said fluid to said chamber and a circuitous

passage for leading said fluid away from said chamber, means adapted to force air through said passage in series, said two passages extending substantially parallel and said fluid flowing therethrough in opposite directions in heat-conductive relation, and means adapted to effect a temperature change in said fluid during its passage, whereby the fluid passing outwardly through said discharge passage gradually approaches atmospheric temperature by heat interchange with the contents of said inlet passage.

13. In apparatus of the class described, in combination, a pair of parallel passages in heat-conducting relation one to the other and connected at their inner ends, means adapted to draw air through said passages in series, a vaporizable cooling agent adapted to be engaged and evaporated by said air prior to its entry into the discharge passage, means adapted to utilize the cooling effect of said air prior to its entry into said discharge passage, and heat-insulating means restricting the heat absorbed in said discharge passage to that taken from the contents of the ingoing passage.

14. In apparatus of the class described, in combination, means forming a chamber adapted to hold the substance to be cooled, means forming a pair of parallel coiled passages in heat-conducting relation one to the other substantially throughout their length, means connecting said passages one with the other adjacent said chamber and adapted to lead air passing in series through said passages about said chamber, means adapted to cause air to flow inwardly through one of said passages and thence outwardly through the other, a vaporizable cooling agent positioned to be exposed to air flowing through said passages prior to its entry into the outward passage, and means preventing the absorption of heat from the outer air into said outward passage while permitting the absorption of heat thereinto from the inward passage.

15. In apparatus of the class described, in combination, means forming a chamber adapted to hold the substance to be cooled, means forming a pair of parallel coiled passages in heat-conducting relation one to the other substantially throughout their length, means connecting said passages one with the other adjacent said chamber and adapted to lead air passing in series through said passages about said chamber, means adapted to cause air to flow inwardly through one of said passages and thence outwardly through the other, a vaporizable cooling agent positioned to be exposed to air flowing through said passages prior to its entry into the outward passage, and means preventing the absorption of heat from the outer air into said outward passage while permitting the ab-

sorption of heat thereinto from the inward passage, said passages being of substantially flat form and spirally disposed about said cooling chamber.

5 16. In apparatus of the class described, in combination, a spirally shaped sheet metal member, means forming a cooling chamber at the center of said spiral and jacketed thereby, a second sheet metal member coiled between the adjacent coils of said first sheet metal member and forming therewith a pair of parallel spiral passages adapted to lead cooling fluid toward and away from said chamber, said passages being connected one 10 with the other adjacent said chamber, and means adapted to cool the air during its travel through said passages.

16 17. In apparatus of the class described, in combination, a spirally shaped sheet metal member, means forming a cooling chamber at the center of said spiral, a second sheet metal member coiled between the adjacent coils of said first sheet metal member and forming therewith a pair of parallel spiral 20 passages leading to said chamber and connected at their inner ends, a moistened absorbent material in one of said passages, and means for forcing a flow of air through said last passage to said chamber and out through 25 said other passage.

25 18. In apparatus of the class described, in combination, a base member, an upstanding spiral wall forming with said base member a cooling chamber substantially at the center 30 of said spiral, a second upstanding spiral wall extending between adjacent coils of said first wall and forming therewith and with said base member a pair of spiral passages for leading cooling fluid toward and 35 away from said chamber and connected one with another adjacent said chamber, a cover for said cooling chamber and said spiral passages, means adapted to cool the air during its travel through said passages, and 40 heat-insulating means substantially encasing said passages and said chamber.

45 19. In apparatus of the class described, in combination, a base member, an upstanding spiral wall forming with said base member a cooling chamber substantially at the center 50 of said spiral, a second upstanding spiral wall extending between adjacent coils of said first wall and forming therewith and with said base member a pair of spiral passages for leading cooling fluid toward and away 55 from said chamber, said walls being formed of heat-conducting material and said passages being free from cross-connection, 60 whereby a single current of air flowing in each is directly embraced by serially spaced currents of air flowing in the other, a cover for said cooling chamber and said spiral 65 passages, means for forcing a flow of air through said passages, and means in said pas-

sage leading to said chamber for cooling said air flow therethrough by evaporation.

In testimony whereof, I have signed my name to this specification this 13th day of May, 1924.
